CLAIM

The ornamental design for a partially shell encased swimming pool chemical tablet, as shown and described.

DESCRIPTION

FIG. 1 is a top perspective view of a partially shell encased swimming pool chemical tablet according to my new design;
FIG. 2 is a top plan view thereof, the bottom being identical;
FIG. 3 is a side elevational view thereof, all sides being identical; and,
FIG. 4 is a partial cross-sectional view thereof.

FIG-1

FIG-2

FIG-3

FIG-4
